UNITED STATES PATENT OFFICE.

GEORGE LEONARD McALPINE, OF CATFORD, ENGLAND, ASSIGNOR TO JOHN J. GRIFFIN & SONS, LIMITED, OF LONDON, ENGLAND.

FIRING MECHANISM OR FUSE FOR EXPLOSIVE BODIES.

1,316,491.

Specification of Letters Patent. Patented Sept. 16, 1919.

Application filed April 22, 1918. Serial No. 230,049.

To all whom it may concern:

Be it known that I, GEORGE LEONARD McALPINE, a subject of the King of Great Britain, residing at 34 Inchmery road, Catford, in the county of Kent, England, have invented certain new and useful Improvements in or Relating to Firing Mechanism or Fuses for Explosive Bodies, of which the following is a specification.

10 This invention relates to delay action firing mechanism or fuses for shells, bombs, mines and other explosive bodies where ignition of the charge is desired after a predetermined interval from the time of setting 15 the fuse, the chief object of the invention being to provide means by which such ignition may take place after considerable delay (from a few minutes to several hours or days according to requirements) within a 20 comparatively small range of error in time.

According to this invention the firing mechanism is retained mechanically by means of a soluble member that is placed at the time of setting under the action of a 25 suitable solvent which slowly acts upon the said member so that at about the end of the predetermined interval the member yields to the mechanical pressure of the firing pin or other firing mechanism which is there- 30 upon released and fires the explosive charge.

A suitable soluble member is found to be a disk or diaphragm of celluloid or like cellulose compound (for example cellulose acetate) that is acted upon by an organic 35 solvent, such as acetone or amyl acetate, the effect of which is gradually to penetrate the celluloid, which absorbs the solvent and weakens until its resistance is insufficient to hold up the firing mechanism. This action 40 is much steadier than an ordinary solvent one in which the solvent material is actually dissolved away from the surface, the rate of solution in this case depending on the concentration of the liquid at the surface 45 and therefore varying if the liquid flows.

A convenient construction embodying my invention comprises a firing pin having a coned or sloping surface meeting the end of a retaining pin or catch the head of which 50 abuts against the soluble disk or diaphragm, the latter being secured in a solvent chamber by a small screwed ring or tubular plug, preferably with a protecting washer between it and the diaphragm. When the 55 fuse is to be set a small quantity of the

solvent is introduced into the said chamber, which is then closed by a screw or other cover or plug. Or the solution may be introduced in a small container arranged to be pierced or otherwise opened on discharge or 60 impact of the shell. When the solvent action has proceeded until the disk is sufficiently weakened the firing pin under its spring pressure is able to push back the retaining pin by the wedge action of the 65 conical or sloping surface, when the firing pin is released and strikes a detonator by means of which the charge is fired.

In order that the said invention may be clearly understood and readily carried into 70 effect, I will describe the same more fully with reference to the accompanying drawings, in which:

Figures 1 to 4 show in section four shell noses illustrating four modifications of the 75 device; and

Fig. 5 is a longitudinal section of a delay action fuse applied to a gaine tube.

A is the shell nose. B is the firing pin with the spring b. C is the retaining pin 80 or catch. D is the soluble member in the form of a diaphragm or disk. E is the chamber receiving the solvent and closed at one end by the disk D.

Referring to the device shown in Fig. 1 85 the firing pin B and the retaining pin C are placed at right angles to each other, the former being made with a sleeve shank fitting over a longitudinal guiding pin b' which is screwed in the tip a of the shell 90 nose, the tip or cap screwing on the end of the nose and allowing of access to the chamber a' in which the firing pin is placed.

The chamber E receiving the solvent is formed laterally in the nose A and is closed 95 by the screw plug e which bears upon the retaining ring e', which is separately screwed into the chamber and secures the soluble disk D in the inner end of the chamber. The head c of the retaining pin C rests 100 against the disk and the inner end of the pin projects forwardly into the chamber a' under the conical head b' of the firing pin.

The operation of the device is as follows:—When the chamber E is filled with 105 the acetone or other solvent and the chamber is again closed by inserting the plug e, the celluloid or other soluble disk is immediately attacked, the solution gradually penetrating the disk until, after an interval 110

which can be calculated with a fair amount of accuracy and which varies according to the thickness of the celluloid, the disk is so softened that the wedging action of the head b^2 of the firing pin is able to press back the retaining pin C, releasing the firing pin which immediately springs forward and strikes the detonator cap carried by the holder a^2 secured in the base of the shell 10 nose.

10 In the modification illustrated in Fig. 2 the principle of operation is the same, but the firing pin B is placed in the lateral chamber a^3 and the solvent chamber E is 15 longitudinal and immediately under the tip or cap a , which serves in place of the plug e in the first construction. The retaining pin C is longitudinal and the soluble disk D lies in the base of the chamber E, 20 the retaining ring e' holding the disk in place through the small steel washer or friction ring e^2 , which prevents abrasion of the disk on screwing up the ring e' .

25 The construction of the firing pin is similar to that shown in Fig. 1, but the guiding pin b' is lateral instead of horizontal and is screwed in the plug a^4 closing the end of the chamber a^3 , at the opposite end of which is fitted the cap a^5 communicating with the 30 detonator a^6 through the small flash passage a^7 . The general operation of the device is as already described in connection with Fig. 1.

35 In the modification shown in Fig. 3, the fuse is arranged to be cocked on discharge and for this purpose the firing pin spring b is normally unenergized and is energized on discharge by the inertia member F which takes the place of the fixed guiding pin b' in the previous construction. This inertia member 40 slides in the chamber a^2 in the tip or cap a and is provided with a guide sleeve extension f receiving the stem b^3 of the firing pin B. The general construction of the fuse is similar to that shown in Fig. 1, the firing 45 pin being longitudinal and the retaining pin lateral. The operation of the device is as follows:—On discharging the shell the set-back of the inertia member F compresses the firing pin spring b, the pin itself being 50 held by the retaining pin C. On compression occurring the two small catch pins f of the inertia member are caused to project outward by the spring f^2 as soon as the inertia member reaches such a point that the 55 pins can project into the annular recess a^8 at the base of the chamber a^8 . The firing pin is then held in energized position and firing can occur as soon as the soluble disk D is sufficiently weakened by the solution to 60 release the firing pin.

65 In Fig. 4 a construction is shown which prevents cocking of the fuse before percussion of the shell. In this arrangement, as in Fig. 3, the firing pin spring b is normally unenergized and the inertia member F' is

arranged to operate in opposite direction to the member F in Fig. 3, its movement occurring on percussion of the shell instead of discharge. The firing pin spring is retained between the head of the inertia member F' and the end of the recess a^8 in the nose tip a , the inertia member projecting into the firing pin, which is made in the form of a separate head. To prevent any danger of the firing pin being released on 70 discharge a safety pin G is provided which extends under the sloping face of the firing pin opposite to the retaining pin C, the safety pin being held by the small catch rod g, the upper end of which meets the flat spring g' which may form a segment of a circle. The safety pin G is held by its catch until percussion of the shell, which causes the rod g to move forward against the spring g' and release the safety pin. 75

80 On percussion of the shell the inertia member F' energizes the spring b and moves forward against the force of the spring until the small catch pins f' engage behind the end of the firing pin B, which is retained by a shoulder in its cavity or recess so that forward movement is prevented. The device is now cocked and on weakening of the soluble disk D the firing pin pushes back both the retaining pin C and the already freed safety pin G and strikes the detonator cap. 85

90 Cocking devices such as are described in connection with Figs. 3 and 4 may be arranged to admit the solvent to the soluble diaphragm on discharge or percussion of the shell; for example, by piercing a container in which the solvent is introduced, so that the timing of the fuse is from discharge or 95 percussion. This action may be in addition to or substitution of the spring energizing operation. 100

105 In Fig. 5 the device is shown as applied to the gaine tube of a shell. In this case the firing pin B is placed to the gaine tube H so as to slide longitudinally therein, the firing pin spring b being compressed between a flange b^4 at the end of the pin B and a shoulder h inside the tube. The outer end of the firing pin B is made with an inverted cone surface b^5 meeting the two opposite retaining pins C. The solvent may be placed in an annular channel h' formed by a sleeve h² screwing on the head of the gaine tube and removed for fitting the soluble diaphragms D and retaining pins C which are secured by the small washer h³ and tubular screwed plug h⁴ through which the solvent reaches the back of the diaphragm. The head of the gaine tube can be closed, after admission of the solution, by a cap screwing 110 on the aforesaid sleeve h². 115

120 The delay action has been shown as applied to shells but it is equally applicable to bombs, mines and other explosive bodies without substantial alteration. 125

What I claim and desire to secure by Letters Patent of the United States is:—

1. In firing mechanism for explosive bodies, a spring operated firing device, a catch adapted to hold up the said device, a diaphragm of cellulose compound such as celluloid against one face of which the catch abuts, for holding up purposes, and means for admitting a slowly acting organic solvent to the other face of said diaphragm, for the purpose specified.

2. In firing mechanism for explosive bodies, a spring operated firing device, a catch adapted to hold up the said device, a diaphragm of cellulose compound against one face of which the catch abuts, for holding up purposes and means for admitting acetone to the other side of the said diaphragm, for the purpose specified.

20 3. In firing mechanism for shells, a spring operated firing device, a soluble retaining member for the said firing device, means for admitting a slowly acting solvent to the said member and means by which the firing device is cocked upon sudden acceleration of the shell on discharge or impact.

4. In firing mechanism for shells, a spring operated firing device, a soluble retaining member for the said firing device, means for admitting a slowly acting solvent to the said member and an inertia device by which the firing device is energized upon sudden acceleration of the shell on discharge or impact.

5. In firing mechanism for shells, a spring operated firing pin of which the spring is normally unenergized, an inertia device adapted to energize the spring upon sudden acceleration of the shell, a catch adapted to hold up the firing pin against the pressure of the energized spring, a soluble diaphragm holding the catch in operative position and means for admitting a slowly acting solvent to the said diaphragm.

6. In firing mechanism for shells, a spring operated firing pin of which the spring is normally unenergized, an inertia member adapted to energize the spring upon sudden acceleration of the shell, a catch holding the spring in energized condition, another catch holding up the firing pin against the pressure of the energized spring, a soluble diaphragm holding the second catch in operative position and means for admitting a slowly acting solvent to the said diaphragm.

7. In firing mechanism for shells, a gaine tube, a spring operated firing pin fitted in the said gaine tube, a catch adapted to hold up the firing pin, a soluble diaphragm against one side of which the catch bears for holding the catch in operative position and a chamber provided in the gaine tube at the other side of the diaphragm adapted to be supplied with a slowly acting solvent which acts upon the said diaphragm, for the purpose specified.

GEORGE LEONARD McALPINE.
